(57) CLAIM

The ornamental design for a container organizer, as shown and described.

DESCRIPTION

FIG. 1 is a Top Left perspective view of the design of the instant invention;

FIG. 2 is a Left Side elevation; and,

FIG. 3 is a Top right plan view.

The rear is plain and unadorned. The particular depth and appearance of the narrow slots on the top surface form no part of the claimed design.

1 Claim, 2 Drawing Sheets
